UNITED STATES PATENT OFFICE.

GEORGE HUMPHRIES, OF HAVERHILL, MASSACHUSETTS.

MOP.

1,092,770.

Specification of Letters Patent. Patented Apr. 7, 1914.

Application filed April 2, 1913. Serial No. 758,398.

To all whom it may concern:

Be it known that I, GEORGE HUMPHRIES, a citizen of the United States, residing at Haverhill, in the county of Essex and State 5 of Massachusetts, have invented an Improvement in Mops, of which the following is a specification.

This invention relates to certain improvements in floor mops, and has for its object 10 to provide a simple, effective, inexpensive and durable means for rigidly securing the material of which the mop is composed to the handle, which will enable the mop to be removed readily from the handle and a new 15 one to be substituted therefor, without difficulty, and which will provide a support or backing for the mop, which will hold it in front of, or beneath the handle, so that it may be forcibly pressed against the floor 20 when used. I accomplish these objects by the means shown in the accompanying drawing in which,

Figure 1 is a side elevation of my device. Fig. 2 is a central longitudinal section thereof 25 taken at the line 2—2 of Fig. 1. Fig. 3 is a detail plan view of the mop connecting plate. Figs. 4, 5 and 6 are detail views showing the mop clamping means before it is attached, Fig. 4 being a section at the line 4—4 30 of Fig. 1, Fig. 5 a side elevation, and Fig. 6 a plan view. Fig. 7 is a detail view of the clamping plate.

As shown in the drawing, the ordinary wooden handle *a* is provided with a ferrule *b* 35 on its end, and an annular disk or connecting plate *c* is connected to the handle by means of a long brad *d* which is passed through a centrally arranged aperture *c'* therein, and driven into the middle of the 40 handle longitudinally thereof, so that the disk *c* is firmly clamped against the end of the handle. The portion of the brad adjacent its head and the hole *c'* are square in form to prevent the disk from turning. Said 45 disk *c* is of rigid sheet metal of dished or concavo-convex form, the convex side being arranged to bear against the end of the handle.

The mop *e* preferably comprises a bundle 50 of strands of hemp, or similar material, the middle portion of the bundle being clamped between a pair of clamping plates *f* and *g*. The bottom plate *f* is approximately circular in form and is provided, at diametrically 55 opposite points, with a pair of ears *f'* which project therefrom at right angles. The up-

per plate *g* may be of approximately rectangular form, as shown, although the particular form is not essential, and is provided with elongated apertures *g'*, at diametrically opposite points, through which the ears *f'* are adapted to pass. The end portions of each of said ears *f'* are split longitudinally, or bifurcated, to provide a pair of binding lugs *f''* and a pair of connecting 60 lugs *f'''*.

In practice the bundle *e* of hemp strands is placed on the plate *f* between its ears *f'*, as shown in Fig. 4, then the plate *g* is placed against the bundle, the ears *f'* being passed 65 through the apertures *g'* in the plate *g*, and then said plates are firmly pressed together by any suitable means. While the plates are 70 thus held pressed against opposite sides of the bundle, the ear sections, or lugs *f''* are 75 bent down onto the plate *g*, and, as the malleable sheet metal, of which the parts are made, is stiff and does not easily bend, the plates will be securely locked together 80 against the expansive force of the bundle. The other lugs or ear sections *f'''* are then 85 passed through the apertures *c''* of the disk *c*, and the concave side of said disk is pressed firmly onto the top plate *g*, as shown in Fig. 4, and then said ear-sections *f'''* are bent outwardly, and downwardly onto the disk *c*, as indicated in Fig. 2. The mop is thus 90 securely connected to the disk *c*, and as said disk has previously been secured to the handle, the parts will all be rigidly connected. 95 The disk *c*, as thus arranged with relation to the mop material, provides a rigid backing therefor, and holds it in front of the handle when pushed along the floor thereby, so that the floor may be forcibly scrubbed with the 100 mop. By providing a connection between the disk and the handle which will not permit the disk to turn with relation thereto, and by providing the ears *f'* at opposite points, the mop will be securely held from 105 turning with relation to the handle. As the concave side of the plate *c* faces downward, it acts to better advantage in holding the mop strands in front of, or beneath the handle, as the mop is pressed against the floor 110 thereby, and also provides a space for the head of the brad *d* and a recess to receive the plate *g*.

The bundle of strands clamped between the plates *f* and *g*, as shown in Fig. 4, may 115 be sold as a separate article of manufacture for renewal, and, when the mop becomes

worn, it may be readily removed by bending up the ear sections f^3 and withdrawing them from the plate c and then inserting the ear sections of the new mop in the apertures of 5 said plate and attaching it in the manner already described. The handle and disk c may thus be used for an indefinite period.

10 The above described construction may be manufactured at small expense, as the plates c , f and g may be died out of sheet metal, and the parts may be easily and quickly assembled.

I claim:

15 1. In combination with a handle, an attaching plate secured to the end thereof, a mop, a pair of clamping plates engaging opposite sides of said mop, two pairs of ears, one pair connected to one clamping plate and extending through and bent into engagement with the other clamping plate, to hold said clamping plates in engagement with the mop, and the other pair connected to one clamping plate and extending through the other clamping plate and through said 20 25 attaching plate and bent into engagement with the latter, substantially as described.

30 2. In combination with a handle, a sheet metal disk having a central aperture and two diametrically opposite apertures, a pair of clamping plates, one having a pair of oppositely disposed apertures and the other having a pair of correspondingly disposed ears extending therethrough, said ears having their end portions bifurcated to provide 35 clamping lugs, one lug of each ear being bent into locking engagement with said apertured plate, and the other lugs extending through the apertures of said disk and

being bent into locking engagement therewith, and a mop disposed between said ears 40 and clamped between said plates, substantially as described.

3. An article of manufacture comprising a pair of metal clamping plates, one having oppositely disposed apertures and the other 45 having two pairs of corresponding disposed ears extending through said apertures, a mop disposed between said ears and clamped between said plates, one pair of said ears having its end portion bent into engagement with the outer side of the apertured plate, and the other pair of ears extending therefrom to provide attaching means substantially as described.

4. An article of manufacture comprising a 55 pair of clamping plates, one having two oppositely disposed apertures and the other having a pair of correspondingly disposed ears and having bifurcated end portions extending through said apertures, a mop disposed between said ears and having said plates pressed against opposite sides thereof, one section of said bifurcated portion of each pair being bent into engagement with the outer side of said apertured plate, to hold said plates in clamping engagement with the mop, and the other sections thereof extending therebeyond to provide attaching means, substantially as described.

5. In testimony whereof, I have signed my 70 name to this specification, in the presence of two subscribing witnesses.

GEORGE HUMPHRIES.
